UNITED STATES PATENT OFFICE.

JOHN P. ORWIT, OF BIG BAY, MICHIGAN.

DESIGN FOR A TOY.

59,675.

Specification for Design. Patented Nov. 15, 1921.

Application filed April 18, 1921. Serial No. 462,446. Term of patent 7 years.

To all whom it may concern:

Be it known that I, JOHN P. ORWIT, a citizen of Lithuania, residing at Big Bay, in the county of Marquette and State of Michigan, have invented a new, original, and ornamental Design for a Toy, of which the following is a specification, reference being had to the accompanying drawing, forming part thereof.

The figure is a perspective view of a toy showing my new design.

I claim:

The ornamental design for a toy, as shown.

JOHN P. ORWIT.

Witnesses:

A. URBON,
C. RANDIS.
